[57] **CLAIM**

The ornamental design for a tub for bathing, as shown and described.

DESCRIPTION

FIG. 1 is a perspective view taken from the top, front, and right side of a tub for bathing showing our new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a bottom plan view thereof; and,

FIG. 7 is a cross-sectional view taken on line 16—16 of FIG. 2.

The fragmentary broken line representations of walls in FIG. 1 are for the purpose of illustration only and form no part of the claimed design.
